CLAIM

The ornamental design for a dual-mode fluid connector, as
shown and described.

DESCRIPTION

FIG. 1 is a top, rear, left side perspective view of a
dual-mode fluid connector, showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom, front, right side perspective view thereof.
The broken lines shown in the figures are for the purpose of
illustrating portions of the article and form no part of the
claimed design.

1 Claim, 8 Drawing Sheets
